Fig. 4.

Fig. 5.

A technical line drawing of a mechanical assembly. It features two main vertical components on the left and right, each with a central cylindrical part and a flared top. Between these are two horizontal rectangular blocks. Various parts are labeled with numbers: '6' at the top left, '38' pointing to the top of the left vertical component, '39' pointing to the top of the right vertical component, '51' pointing to the top of the left horizontal block, '52' pointing to the top of the right horizontal block, '58' pointing to the left of the left vertical component, '41' pointing to the left of the right vertical component, and '53' pointing to the bottom of both horizontal blocks.

FUSE PANEL

Application filed June 8, 1927. Serial No. 197,389.

Our invention relates to fuse panels and particularly to fuse blocks of the character used in enclosed distributing panels.

One object of our invention is to provide 5 a panel block containing a plurality of fuse receptacles which may be assembled as a unit within a panel housing to provide any desired number of branch line fuse circuits.

Another object of our invention is to provide 10 a fuse panel block wherein a pair of fuse receptacles associated with a load circuit are arranged in a horizontal row and wherein the fuses of a neighborhood load circuit are similarly arranged in a row parallel with the 15 first row.

Another object of our invention is to provide 20 terminal facilities for the fuse receptacles that may be readily assembled upon the block in such manner that they are separated by the distance required by the Bureau of Fire Underwriters.

Another object of our invention is to provide 25 a fuse block wherein the fuse receptacle terminals are disposed in notches in the end of the block, in such manner that no part of the terminals project from the block, thereby preventing the conductors in the wiring gutter from engaging live terminals of neighboring blocks.

These and other objects that will be made 30 apparent throughout the further description of our invention are attained by means of the panel block hereinafter described and illustrated in the accompanying drawings, 35 wherein;

Figure 1 is a plan view of a panel housing with the door removed and equipped with our improved panel blocks.

Fig. 2 is a transverse section taken on the 40 line II—II of Fig. 1, showing the panel block in side elevation.

Fig. 3 is a bottom plan view of an improved panel block embodying features of our invention.

Fig. 4 is a top plan view of the block shown 45 in Fig. 1.

Fig. 5 is a longitudinal section through a block taken on the line V—V of Fig. 4, and

Fig. 6 is an end view of the block.

Referring to the drawing, the usual panel

housing comprises a sheet metal box or casting 7 that is provided with a cover plate or trim 8 having a centrally disposed rectangular opening 9 usually closed by means of a hinged door (not shown). 55

In the usual panel construction the fuse blocks 11 and end blocks 12 and 13 are mounted upon Z-bars 14 that are secured to the bottom or rear wall of the housing, the blocks being secured thereto by means of screws 15. 60 The bus bars 16, 17 and 18 are disposed beneath the blocks, and the terminal ends 19 thereof are covered by the detachable block 12. The insulating block 13 serves to cover the neutral bus bar 21 to which the return 65 conductors from each load circuit are connected.

Referring to Figs. 3 to 6, each fuse block 11 comprises an insulating block having a recess 22 in the rear or underside thereof, which 70 communicates with passages 23 in the end walls 24 of the block. The end walls project beyond the rear face of the block to provide a space 25 in which the bus bars 16, 17 and 18 are disposed and supported in a manner that 75 will be hereinafter described.

Four pairs, 26, 27, 28 and 29, of fuse receptacle sockets 31 are provided in the front face of the block for receiving pairs of load circuit fuse receptacles 32 and 33 which are 80 of the usual screw shell type for receiving screw plug fuses. The sockets 31, for the receptacles 32 and 33 are provided with openings 34 and 35 respectively, which communicate with the recess 22 in the underside of the 85 block and through which terminal strips 36 and 37 extend into the recess, the terminal 36 extending through the passage 23 and terminating adjacent the end of the block where it is provided with an attaching screw 38 90 which extends into a groove 39 in the end of the block.

Terminal extensions 41 are detachably secured to the terminals 37. The extensions 95 terminals 41 are made of sheet metal stampings, each having end portions 41a and 41b disposed parallel with the front face of the block and a central portion 41c turned at right angles thereto and which is offset to clear the insulating bushings 42 that are dis- 100

posed directly opposite the sockets 31 for the receptacles 32 and which surround conductor bushings 43 which constitute the central terminals of the fuse receptacles. The 5 bushings 43 are insulated from the receptacle by insulating washers 44.

This arrangement of the terminals 36 and 41 provides ample space between the conductor terminals and between the terminals 41 10 of neighboring feed circuits. Center terminal bushings 45 are surrounded by integral insulating bushings 46 opposite the sockets 31 containing the fuse receptacles 33. These bushings are insulated from the terminal 37 15 by insulating washers 47. The conductor bushings 43 and 45 are in the form of hollow rivets which are peened over the ends of the insulating bushings and serve to hold the receptacles 32 and 33 in assembled position.

20 The bus bars 16, 17 and 18 are, as indicated in Fig. 2, secured in conductive contact with the inner ends of the bushings 43 and 45 by means of screws 48 that extend through the bushings and are threaded into threaded holes 25 provided in the bus bars. It will be seen therefore that the bus bars are securely attached to the insulating bushings and that this operation may be performed before the bushings are secured within the panel housing. 30

Referring to Figs. 5 and 6, it will be noted that the terminal extensions 41 terminate in grooves 51 which constitute a part of the passages 23 and that they are provided with attaching screws 52 having their threaded ends extending into notches 53 in the end wall.

35 The insulating block 11 is provided adjacent its ends with notches 54 for receiving the depending flange 55 that is carried by the trim 8 and which serves to preclude access to the wiring gutters 56 at the sides and ends of the insulating blocks through the opening 9 in the trim.

40 As previously pointed out, none of the fuse receptacle terminals project beyond the end of the block and consequently the conductors within the wiring gutter cannot engage exposed portions of the fuse terminals of neighboring fuse blocks.

45 It will be understood that since the fuse blocks are identical, any number of them may be provided in a fuse panel housing to accommodate any desired number of load circuits, and that by reason of the construction where- 50 in the fuse receptacle terminals are rendered readily accessible when the trim is removed, the wiring is greatly facilitated, and there is little or no danger of short-circuits occurring. The construction is rugged and inexpensive to manufacture and is relatively compact and 55 neat in appearance.

60 While we have illustrated but one embodiment of our invention, it will be apparent to those skilled in the art that various changes, 65 modifications, substitutions, additions and

omissions may be made in the apparatus illustrated without departing from the spirit and scope of our invention, as set forth in the appended claims.

We claim as our invention:

1. A fuse panel block comprising an insulating block having a pair of sockets in the front face disposed in a line extending longitudinally of the block and having a recess in the rear face of the block, the end wall of the block being provided with a passage communicating with the said recess, and the said sockets being provided with openings communicating with the said recess, and fuse receptacles within the sockets, each having a terminal extending through the said openings and through the said passage in the end wall. 70

2. A fuse panel block comprising an insulating block having a pair of sockets in the front face disposed in a line extending longitudinally of the block and having a recess in the rear face of the block, the end wall of the block being provided with a passage communicating with the said recess, and the said sockets being provided with openings communicating with the said recess, and fuse receptacles within the sockets, each having a terminal extending through the said openings and through the said passage in the end wall, one of the said terminals being offset with respect to the center line of the sockets. 80

3. A fuse panel block comprising an insulating block having a pair of sockets in the front face disposed in a line extending longitudinally of the block, and having a recess in the rear face of the block, the end wall of the block being provided with a passage communicating with the said recess, and the said sockets being provided with openings communicating with the said recess, and fuse receptacles within the sockets, each having a terminal extending through the said openings and through the said passage in the end wall, one of the said terminals being offset with respect to the center line of the sockets, and comprising a flat metal strip having its central portion bent at right angles to its end portions. 100

4. A fuse panel block comprising an insulating block having a pair of sockets in the front face disposed in a line extending longitudinally of the block and having a recess in the rear face of the block, the end wall of the block being provided with a passage communicating with the said recess, and the said sockets being provided with openings communicating with the said recess, and fuse receptacles within the sockets, each having a terminal extending through the said openings and through the said passage in the end wall, one of the said terminals being offset with respect to the center lines of the sockets, and comprising a flat metal strip having its central portion bent at right angles to its end portions and its free end located in a different 110 120 125 130

plane from that of the free end of the other terminal.

5. A fuse panel block comprising an insulating block having a recess in its rear face communicating with a passage through its end wall and having two pairs of sockets arranged longitudinally of the block in rows and in side by side relation, each socket being provided with an opening communicating with the said recess, and fuse receptacles within the sockets, each having a terminal extending through the said openings and through the said passage in the end wall.

15 6. A fuse panel block comprising an insulating block having a recess in its rear face communicating with a passage through its end wall and having two pairs of sockets arranged longitudinally of the block in rows 20 and in side by side relation, each socket being provided with an opening communicating with the said recess and fuse receptacles within the sockets, each having a terminal extending through the said openings and 25 through the said passage in the end wall, center terminals within the receptacles and insulated therefrom and extending through and surrounded by the material of the block and terminating exteriorly of the rear face 30 of the block, the said first said terminals of the receptacles remote from the said end of the block being offset toward the axis of the block and extending between the center terminals of the receptacles nearest to the said 35 end of the block.

7. A fuse panel block comprising an insulating block having end walls projecting from the rear face of the block to constitute supporting legs therefor and having a recess in the rear face communicating with passages extending through the end walls, the said block having two longitudinal rows of sockets having openings communicating with the said recess, receptacles in the sockets having 40 terminals extending through the said openings and terminating in the said passage in the end walls, center terminals within the receptacles insulated therefrom and extending through and surrounded by the material of 45 the block and terminating exteriorly of the rear face of the block, the first said terminals of the innermost receptacles being offset and extending between the center terminals of the outermost receptacles.

55 8. A fuse panel block comprising an insulating block having end walls projecting from the rear face of the block to constitute supporting legs therefor and having a recess in the rear face communicating with 60 passages extending through the end walls, the said block having two longitudinal rows of sockets having openings communicating with the said recess, receptacles in the sockets having terminals extending through the 65 said openings and terminating in the said

passages in the end walls, center terminals within the receptacles insulated therefrom and extending through and surrounded by the material of the block and terminating exteriorly of the rear face of the block, the first 70 said terminals of the innermost receptacles being offset and extending between the center terminals of the outermost receptacles, the said center terminals being adapted to engage the feed conductors or bus bars disposed 75 beneath the block.

9. A fuse panel block comprising an insulating block having a recess in its rear face communicating with a passage through its end wall and having two pairs of sockets arranged longitudinally of the block in rows in side-by-side relation, each socket being provided with an opening communicating with the said recess, and fuse receptacles within the sockets, each having a terminal extending 80 through the said openings and through the said passage in the end wall, the said terminals of each pair being disposed in different planes.

In testimony whereof, we have hereunto 90 subscribed our names this 28th day of May, 1927.
